(57) **CLAIM**

The ornamental design for a wrench for sprinkler head, as shown and described.

DESCRIPTION

FIG. 1 is a front elevational view of a wrench for sprinkler head showing my new design, a rear elevational view thereof being a mirror image;

FIG. 2 is a right side view thereof; a left side elevational view thereof being a mirror image;

FIG. 3 is a top plan view thereof;

FIG. 4 is a bottom plan view thereof; and,

FIG. 5 is a cross-sectional view thereof taken along the line 5-5 shown in FIG. 3.
